UNITED STATES PATENT OFFICE.

HEINRICH THIEMANN, OF DESSAU, GERMANY.

SLIPPER.

SPECIFICATION forming part of Letters Patent No. 787,481, dated April 18, 1905.

Application filed February 10, 1904. Serial No. 192,944.

To all whom it may concern:

Be it known that I, HEINRICH THIEMANN, a subject of the Duke of Anhalt, residing at 22 Elisabethstrasse, Dessau, in the Duchy of Anhalt and Empire of Germany, have invented new and useful Improvements in Slippers, of which the following is a specification.

This invention relates to a paper slipper, which consists in its body—that is to say, in sole and upper—of one piece.

This slipper differs from such heretofore known in that on each side of the upper one part of the double sole is fastened. A heel part may be provided on one of the soles, so as to make a shoe of the slipper. The folded parts are connected with each other in any desired manner at the points where they meet. This may be effected by sewing them with thread, yarn, &c., by fastening them together with wire clamps, rivets, &c., by gluing, or in any other way, it being understood that the manner of fastening them together does not form part of the present invention.

The invention is shown in the accompanying drawings in various forms.

Figures 1 and 5 show the blank used in each instance. Figs. 2 and 6 show the slipper in side view. Figs. 3 and 7 are top views. Figs. 4 and 8 show it in a section on the lines 4 4 and 8 8 in Figs. 2 and 6. Figs. 1 to 4 and 5 to 8 belong to one constructional form each.

In the constructional form according to Figs. 1 to 4 the blank, Fig. 1, consists of two soles *a* and *b*, connected with each other by the strengthening-piece *c*, which soles fall over each other when the blank is bent or folded along the hatched parts *d d'*, wherein the gluing edge *e*, provided at the front edge of the strengthening-piece *c*, is fastened between the two soles *a* and *b*. The bands *f, f'*, and *g* serve for the reinforcement of the upper, the latter band serving particularly for protection against tearing of the edge of the upper.

The constructional form according to Figs. 5 to 8 differs from the one illustrated in Figs. 1 to 4 merely in that the blank carries on the one sole an additional piece *h*, which when the blank is folded along the hatched lines *d, d',* and *d''* forms a heel part. In the same manner as the gluing edge *e* is fastened on the upper *c* between the front parts of the two soles *a* and *b* the gluing edge *i* of the additional piece *h* is fastened between the rear parts of the soles *a* and *b*. It is expedient to bind also the upper edge of the heel part *h* by a band *j*, of woven material, and at the lower edge of the upper or at any other desired point a strengthening-band *k* may also be provided in all the constructional forms described.

Having thus described my invention, what I claim as new, and desire to secure by Letters Patent, is—

1. A slipper consisting of an upper, and independent soles which are separately connected to the respective sides of the upper and superposed on each other.

2. A slipper consisting of an upper, independent soles which are separately connected to the respective sides of the upper and superposed on each other, and a heel-piece connected to said slipper.

3. A slipper consisting of an upper, independent soles which are separately connected to the respective sides of the upper and superposed on each other, and a heel-piece joined only to one of the soles in the slipper-blank.

In testimony whereof I have signed my name to this specification in the presence of two subscribing witnesses.

HEINRICH THIEMANN.
